Patented Feb. 8, 1927.

UNITED STATES PATENT OFFICE.

WILLIAM G. RITCHIE, OF SALT LAKE CITY, UTAH.

LIFTING JACK.

Application filed February 10, 1926. Serial No. 87,278.

This invention relates to a two-fold jack, and has for one of its objects the lifting of a load in less time and with less power than the jacks now used.

Another object of this invention is to provide a new means for rising the jack, with cams, a block and tackle operated by a set of gears within a handle of the jack.

With these and other objects in view, my invention consists of the following arrangement of parts illustrated in the drawings, in which—

Figure 1 is a side view of my invention showing it in a raised position as in raising 15 a load.

Fig. 2, is a side view of a saddle 15.

Fig. 3, is an end view of a cap 7.

Fig. 4, is a plan view of cap 7.

Fig. 5, is a plan view of the invention.

Fig. 6, is a view on line 6—6 Fig. 7.

Fig. 7, is a side view of the invention showing the jack closed.

Fig. 8, is a view on line 8—8 Fig. 7, showing a plan of block and tackle.

Similar letters and numerals refer to like parts throughout the several views of the drawings.

The reference character, A denotes the front, B the back.

The invention comprises a base having a vertical projection 1 thereon, said projection has a slot 2 in each side thereof and a slot 3 in the front and back thereof. Each corner of the projection 1 has a hole 4 therein extending the full length thereof. On the front and at each side of the slot 3 is a projection 5 which has a slot 6 therein.

A removable cap 7 is placed on the top of the vertical projection 1. Projecting from the bottom of cap 7 is a lug 8 which is placed within the slots 3 and has a notch 9 therein. In the corners of the cap 7 is placed a hole 13 into which is secured a bolt or rod 12 that operates within the holes 4 of the projection 1. On each side and in the center of the cap are other holes 11 through which the legs 14 of the saddle 15 pass through and into the slots 2.

In the lifting of the saddle 15 two cams 50 are used. In the lower end of cam 16 is placed a pin or bearing 18 and in the upper end of cam 17 is also placed a pin or bearing 18', see Fig. 1.

In the face of each cam is a groove 19 and 55 in the outer end of each cam a pin 20 is placed over which one end of cables 21 is se-

cured. When the jack is closed the cable will be within the grooves 19. After the cables have been attached to the pin 20 the other ends are placed through the slots 3 and 60 then secured to a ring 22 which is placed over a hook 23.

Slidably secured to the projections 5 is a socket 27 which receives one end of the handle 26. This socket is secured to the slot by 65 a pin 50 in the sides thereof which slides within the slot 6. The handle 26 is removable from said socket when jack is not in use.

Within the handle is placed a block and tackle comprising a drum 47 having teeth 70 28 on one side thereof which mesh with teeth on a driving gear 29. A pulley 25 is journaled within said handle by a shaft 41 to which one end of a cable 42 is attached. The cable passes under a pulley 24 and then 75 over the pulley 25 and then over to the drum 47 to which the end is secured. To the journal of the pulley 24 is pivotally placed the hook 23. To the shaft of the driving gear 29 is attached a crank 35 for operating the block and tackle. A pawl 34 is placed within the handle to engage the teeth of the gear 29 to prevent the unwinding of the drum 80 when the jack is raised.

In the operation of the invention, the ring 22 is placed on the hook 23. The handle is then placed into socket 27. Crank handle 31 is now operated to wind cable 42 onto drum 47 which draws pulley 24 toward 90 the drum which in turn draws on cables 42 to bring the outer ends of cams 16 and 17 together. In this movement cam 16 pivots on pin 18 bearing in slot 3. The pin 18' on cam 17 raises and moves saddle upward to 95 notch 9 in cap 7. The pin now enters the notch 9 to lift cap 7 upward which will raise bolts 12 in holes 4 to the height of the lift of the cams. In turning handle 31 it operates gear 29 which in turn operates drum 100 47. Pawl 34 catches in teeth of gear 29 and locking said gear to prevent the unwinding of said cable on the drum.

To lower saddle, pawl 34 is removed out of the teeth of gear 29 and the handle 31 105 is turned in the opposite direction from the raising thereof.

Having described my invention, what I claim as new and desire to secure by Letters Patent, is:

1. A lifting jack comprising a base having 110 an upright thereon, said upright having

notches therein and a hole in each corner thereof, a cap having rods thereon, said rods to fit in said holes, a saddle having legs thereon, means in said cap through which said legs pass, cams operating in said upright for raising said saddle and means for operating said cams, all substantially as set forth.

2. A lifting jack comprising a base, a pair of cams pivotally mounted in said base, one of said cams being above the other of said cams, each of said cams have a groove in the face thereof and a pin in the outer end thereof to which is attached a cable, said cable passing through said grooves when said jack is in a closed position, the other end of said cables has a ring thereon which is placed over a hook in the handle of said jack, means in said handle for operating said cam and means for locking said cams when the jack has a load thereon, all substantially as set forth.

3. A lifting jack comprising a base having slots therein, a pair of cams operating in said slots, each of said cams have a groove therein in which is placed a cable one end thereof being attached to its cam and the other end thereof being attached to a ring, said jack having a removable handle slid-

ably secured to said base, a block and tackle within said handle, said ring to be placed 30 on a hook of said block and tackle, said block and tackle to draw on said cables and bring the outer ends of the cams together for the raising of the jack and means for locking said jack when in a raised position, all substantially as set forth.

4. A lifting jack comprising a base having slots therein and holes in the corners thereof, a cap for said base having rods projecting therefrom, said rods to fit within 40 said holes, a cam pivotally operated in said grooves, another cam slidably operative in said grooves, a saddle having legs thereon, said legs passing through holes in said cap into said slots and resting upon a pin in said 45 other cam, a removable handle slidably mounted on said base, a block and tackle within said handle, means attached to said cams and to said block and tackle for operating said cams to raise said saddle, means on 50 said handle for operating said block and tackle and means for locking said cams in a raised position, all substantially as set forth.

In witness whereof I affix my signature.

WILLIAM G. RITCHIE.
